DESIGN FOR A BRACELET OR SIMILAR ARTICLE

Dwight H. Millard, Norwalk, Calif.

Application July 2, 1945, Serial No. 120,467

Term of patent 7 years

(Cl. D45—4)

To all whom it may concern:

Be it known that I, Dwight H. Millard, a citizen of the United States, residing in Norwalk, in the county of Los Angeles, State of California, have invented a new, original, and ornamental Design for a Bracelet or Similar Article, of which the following is a specification, reference being had to the accompanying drawing, forming a part thereof.

The end region at the left side of Figures 1 and 2 corresponding to the end region at the right side of such figures is similar to Figure 3 reversed.

The essential features of my design reside in the parts shown in full lines.

I claim:

The ornamental design for a bracelet or similar article, as shown and described.

DWIGHT H. MILLARD.
